WILLIAM M. KIRCHNER, OF PITTSBURG, PENNSYLVANIA, ASSIGNOR TO
BAKEWELL, PEARS & CO., OF SAME PLACE.

Design No. 3,954, dated April 5, 1870.

DESIGN FOR THE ORNAMENTATION OF GLASS-WARE.

The Schedule referred to in these Letters Patent and making part of the same.

To all whom it may concern:

Be it known that I, WILLIAM M. KIRCHNER, of Pittsburgh, in the county of Allegheny and State of Pennsylvania, have invented a new and improved Design for ornamentation of Glass-ware; and I do hereby declare the following to be a full, clear, and exact description thereof, reference being had to the accompanying drawing making a part of this specification, said drawing illustrating my improved design by a plan view thereof on a section of a glass bowl.

My improved design consists of an arrangement in clusters or bunches, of cherry-leaves, stems, and berries or fruit, and that its distinctive features may be more readily understood I will proceed to describe the same.

The section *a* represents a part of a glass dish, of which *a'* is the edge or rim, and *a''* is the center, which latter may be of knob form, as in the cover of a fruit-dish, or may be the stem or foot of a bowl.

Around the central part *a''* my improved design is repeated in the form shown.

From a waving or twining twig, *b*, of roughened or reticulated work, grow the leaf-stems *c*, leaves *c'*, fruit-stems *e*, and berries or fruit *e'*. All are of raised work or *in relief*.

The berries are of plain globular form, and the leaves are roughened on their face, and have plain inclined edges.

What I claim as my invention, and desire to secure by Letters Patent, is—

The design for ornamentation of glass-ware, consisting of cherry-twigs, stems, leaves, and fruit or berries, arranged substantially as shown and described.

In testimony whereof, I, the said WILLIAM M. KIRCHNER, have hereunto set my hand.

WM. M. KIRCHNER.
